MACHINE FOR BENDING PIPES

Philip H. Woods, Raleigh, N. C.

Application September 23, 1949, Serial No. 117,460

6 Claims. (Cl. 153—46)

1

The present invention relates to machines for bending hollow or solid metallic rod stock. While the machine is of general universal application where it is desired to bend any type of stock in an arc, its novel construction resulting in a design that operates close to the floor without need for anchoring thereto and which is structurally strong but yet relatively light in weight makes the improved machine especially suited for portable use for on-the-job bending of copper or iron tubing in the fabrication of floor type radiant heating coils from the stock. The completed floor coils usually consist of several lengths of the tubular stock joined together and containing a large number of 180° bends. Warm water is then circulated through the coils as a heating medium.

When making up the coil, it is preferable to begin at one side of the floor, placing the lengths of tubular stock in place progressively, joining the ends, and making the 180° bends one after the other until the other side of the floor is reached. Such procedure calls for a pipe bending machine essentially portable, i. e. light in weight, that can be easily carried about the job from place to place when the bends are to be made. Moreover the machine must be of such design that it can operate close to the floor to the end that the coil will be left in proper position without further handling when all bends have been made, i. e. each bend must be made close to the floor so as not to disturb the run of piping behind the machine.

Another object of the invention is to provide a stock bending machine having a reversible drive thereby enabling the machine to be powered in either direction of operation by the conventional portable drill tool motor which is capable of rotating in only one direction.

Yet another object is to provide a stock bending machine in which all forces and counter forces, torques and counter torques are effected within the machine itself. No external force or torque between the machine and the floor or other base upon which it rests is thus necessary to maintain the same stationary while in use and consequently the machine has a very high strength/weight ratio making it possible to operate on comparatively heavy stock with a relatively light weight machine.

A still further object of the invention is to provide a stock bending machine that is easily and quickly adaptable to operate on various sizes and configurations of stock.

The foregoing as well as other objects and advantages inherent in the invention will become more readily apparent from the following detailed description of a preferred structural embodiment thereof and the accompanying drawings in which:

2

Fig. 1 is a top plan of the improved machine; Fig. 2 is a side elevation; Figs. 3 and 4 are end elevations; Fig. 5 is a vertical section on line 5—5 of Fig. 1; Figs. 6 and 7 are horizontal sections on lines 6—6 and 7—7 of Fig. 5; and

Fig. 8 is a fragmentary horizontal sectional detail of the block and sweep arm.

Referring now to the drawings, the bending machine is seen to be comprised of two principal components, these being a stationary and generally rounded block member 1 and a pair of sweep arm members 2, 3 located adjacent the upper and lower faces of the block and pivoted on the latter, the arms being coupled at their outer ends by a dog 4 between which and the rounded periphery of the block the desired bend in the pipe 5 (outlined in broken lines) is formed.

The stationary block 1 has an arcuate periphery 6 with a center of radius coincident with the axis x—x (see Fig. 5), and which contains a groove 7 constituting one of the two forming surfaces for the stock. The configuration of groove 7 in the plane of its radius will of course be determined by the cross-section of the stock to be bent. The present embodiment is designed specifically for bending pipe or other like stock of circular cross-section and hence groove 7 is semi-circular. Block 1 is also provided with an arcuate slot 8 on the same radius as groove 7 and one edge of the slot is toothed to provide an internal arcuate rack gear 9.

The upper and lower sweep arms 2, 3 are pivotally connected to block 1 for rotation about vertical axis x—x by means of sleeve type bearings, the sleeves 10 being carried by the arms, and the bearing shafts 11 being carried by block 1.

Upstanding upon the upper arm 2 and forming an integral part thereof is a case 12 that encloses compound reduction gearing for transmitting power applied to one of three input shafts 13, 14, 15 to the output shaft 16 in order to effect a rotation of the arms 2, 3 about the block 1.

The two input shafts 13, 14 located generally centrally of the block member, which project vertically upward through and are journalled in a common boss 12c on cover 12a of case 12, are provided at their upper ends with hexagonal sockets 17, 18 respectively to receive a complementary configured arbor 19 that is adapted to be chucked at 20 to a conventional portable motor 21. Meshed input pinions 23, 24 are provided at the lower ends of shafts 13, 14 and pinion 23 meshes with a large gear 25 secured to the third input shaft 15 that is journalled in bearing sleeves carried by the cover 12a and bottom wall 12b of the gear case. A hexagonal socket 26 is secured to the upper end of shaft 15

and a pinion gear 27 secured to the lower end thereof meshes with a large gear 28 secured to the upper end of the output shaft 16 that is journalled in vertically aligned bearing sleeves carried by the upper and lower sweep arms 2, 3. Output shaft 16 extends through the arcuate slot 8 in block 1 and carries a pinion gear 29 that meshes with the internal rack gear 9.

Motor 21 is adapted to be supported by the cover 12a of the gear case above and in general alignment with the input shafts 13, 14 and for this purpose two upright posts 32, 33 are provided respectively at the front and rear of the cover. The lower ends of these are received in recessed bosses 34 in the cover and struts 35 at each side of the posts anchored by capscrews 36 that extend through cover 12a into threaded recesses in the case side walls provide vertical rigidity for the posts. The upper ends of posts 32, 33 are internally threaded at 37 to receive threaded studs 38, 39 that carry yokes 40, 41 for supporting the motor handles 43, 44. Yoke 40 is of the double type providing two cradles 40a, 40b for the handle 43, and yoke 41 has but one cradle 41a to receive the oppositely extending handle 44 in which is incorporated a trigger 45 for turning the motor switch on and off.

Yokes 40 and 41 are centered along the central longitudinal axis of the machine. Hence cradle 41a is centered along such axis while cradles 40a, 40b are on each side thereof. Thus when handle 43 is carried by cradle 40a, the motor chuck 20 will be aligned with socket 17 and when carried by cradle 40b, the chuck will be aligned with socket 18.

For supporting the block 1 on a floor or the like, a base consisting of two legs 46, 47 arranged at right angles in the form of a cross is utilized. A screw 48 extends through the legs 46, 47 at the center of the cross into the lower end of the bearing shaft 11 to support the block at this point, and another screw 49 extends through leg 47 into the lower end of a yoke 50 projecting from the rear side of the block 1.

Yoke 50 serves as the support for an anchor 51 that secures the stock in place during the bending operation. Anchor 51 includes a hook 52 adapted to fit over the stock 5, a threaded stud 53 to which hook 52 is pivotally connected and a yoke 54 into which stud 53 is threaded, the yoke 54 being detachably fastened to yoke 50 by means of two sets of complementary pins and apertures 55, 56 provided on the yoke arms.

The improved machine can be used for bending several differently sized rods to several different radii. As illustrated in Figs. 1-7 the machine is set up to bend pipe stock 5 of outside diameter d about a radius r . For such purpose, a half round filler band 57 of internal diameter d and outside diameter d' is employed, the band being seated in the half round groove 7 of diameter d' provided in the periphery of block 1 and secured thereto by screws 58.

Confronting the filler band 57 is another half round groove 59 of diameter d provided in one face of the triangular dog 4 located between the outer end portions of sweep arms 2, 3 and adapted to be connected to the latter by means of a headed through pin 61 that is selectively engageable with any of three sets 62-64 of vertically aligned apertures in the sweep arms. As illustrated the pin is located in aperture set 62 nearest the axis of rotation $x-x$ of the sweep arms. The pipe stock 5 is placed between the two grooves and will of course be bent to the radius r as the

sweep arms and dog are caused to move around the block.

For bending larger pipe stock having an outside diameter d' corresponding to the diameter of the groove 7 without the filler band 57, the latter is removed from the block 1 and dog 4 rotated to bring groove 65 in a second face thereof and having the same diameter d' as groove 7 into confronting relation with groove 7. The larger pipe will of course be bent to the same radius r .

For bending pipe having an outside diameter d to a larger radius than r , a filler band 66 as shown in Fig. 8 is used, this band having an internal half round rib 67 adapted to be seated in groove 7 and an external half round groove 68 is the same diameter as pipe 5. Filler band 66 can be secured to block 1 in the same manner as band 57 and the proper groove in the dog to be used will of course be groove 59. However in this case, dog 4 will be moved outwardly of the sweep arms to the next set of apertures 63, the distance between the centers of aperture sets 62, 63 corresponding of course to the change in radius.

For bending even larger sized pipe the third side of dog 4 is seen to be provided with a groove 69 larger than the other two and would co-operate with a filler band similar to band 66 in Fig. 8 and provided with a groove of the same size as groove 68.

Operation

Assuming the sweep arms 2, 3 to be in a position 90° clockwise from the one illustrated in the drawings, the pipe 5 is run between dog 4 and groove 7 and through hook 52 to the place where the bend is to be made. Motor 21 is then put in place with the motor shaft chucked to socket 17 and turned on by actuating switch control trigger 45. The power input to pinion 23 is transmitted through the compound reduction gearing to the output pinion 29 causing the latter to move counter clockwise in an arc along the internal rack gear 9. Since output pinion 29 is mounted on shaft 16 and the latter is journalled in sweep arms 2, 3, the arms will of course be rotated slowly about block 1 in a counter clockwise direction causing the pipe to be bent around the block up to a maximum bend of 180°. A lug 70 at one side of block 1 serves as a stop for the sweep arms when moving counter clockwise, and a similar lug at the other side of the block serves a like purpose when the arms rotate clockwise. The arms 2, 3 can then be run back to the starting position for a repeat operation by shifting motor 21 over to the other socket 18. This of course reverses the direction of the drive.

If a clockwise bend as measured from the anchor point is required in the pipe, the anchor 51 can be rotated on its pivotal support to the other side of the block and the pipe anchored on such side in which case the driving torque would then be through socket 18.

For comparatively light stock a higher speed operation by hand is possible in which case the motor can be replaced by a hand crank 71 that engages socket 26 to rotate shaft 15 and gears 25 and 27 directly.

When motor 21 is used to drive the sweep arms 2, 3, the necessary counter torque to prevent relative movement between block 1 and the arms is developed internally in the machine by virtue of the fact that motor 21 is carried by the sweep arms. Thus the block 1 does not have to be bolted to the floor. When the hand crank 71 is however used to rotate the sweep arms, there

will be a torque between the floor or other support and the block but this can be absorbed by securing the block to the support such as by bolting down the arms 46, 47 or by an application of a staying pressure from the foot of the operator.

In conclusion, I wish it to be understood that while the particular machine construction described and illustrated is preferred, various changes in the structural details and arrangement of component parts may be made by others without however departing from the spirit and scope of the invention as defined in the appended claims.

I claim:

1. In a stock bending machine, the combination comprising a stationary block member having an arcuate periphery, a sweep arm pivoted to said block member for rotation about the periphery thereof on an axis coincident with the center of radius of the periphery, reduction gearing carried by said sweep arm, said gearing including a pair of meshed input pinions each provided with a drive shaft, a ring gear meshed with one of said input pinions and an output pinion meshed with a stationary arcuate rack gear provided on said block member, means for supporting a motor on said sweep arm to provide a driving torque to either of said drive shafts, and a dog carried by said sweep arm cooperative with the periphery of said block member.

2. In a stock bending machine, the combination comprising a stationary block member having an arcuate periphery, a sweep arm pivoted to said block member for rotation about the periphery thereof on an axis coincident with the center of radius of the periphery, reduction gearing carried by said sweep arm, said gearing including a pair of meshed input pinions each provided with a drive shaft, a ring gear meshed with one of said input pinions and an output pinion meshed with a stationary arcuate internal rack gear provided on said block member, means for supporting a motor on said sweep arm to provide a driving torque to either of said drive shafts, and a dog carried by said sweep arm cooperative with the periphery of said block member.

3. A portable stock bending machine comprising, a stationary block adapted to rest in a horizontal position closely adjacent the floor, said block having an external arcuate grooved periphery and a stationary arcuate rack gear arranged internal to and concentric with said periphery, upper and lower sweep arms disposed adjacent the upper and lower faces respectively of said block and extending beyond the periphery thereof, means pivotally mounting said arms on said block for rotation on a common vertical axis coincident with the center of radius of said periphery, a dog disposed between and secured to both of said sweep arms beyond the periphery of said block, an output shaft including a pinion located between said sweep arms and meshed with said internal rack gear, vertically aligned bearing means in said upper and lower sweep arms journaling said output shaft, an input shaft, and reduction gearing extending between said input and output shafts, said input shaft and reduction gearing being carried by said upper sweep arm.

4. A portable stock bending machine comprising, a stationary block member adapted to rest in a horizontal position closely adjacent the floor, said block member having an external arcuate grooved periphery and a stationary arcuate rack gear arranged internal to and concentric with

said periphery, upper and lower sweep arm members disposed adjacent the upper and lower faces respectively of said block member and extending beyond the periphery thereof, means pivotally mounting said arm members on said block member for rotation on a common vertical axis coincident with the center of radius of said periphery, a dog disposed between and secured to both of said sweep arm members beyond the periphery of said block member, an output shaft

15 including a pinion located between said sweep arm members and meshed with said internal rack gear, vertically aligned bearing means in said upper and lower sweep arm members journaling said output shaft, an input shaft rotatable on a vertical axis located generally centrally of said block member, reduction gearing extending between said input and output shafts, said input shaft and reduction gearing being carried by said upper sweep arm member, and a motor carried by one of said members, said motor being disposed above and in general alignment with and coupled to said input shaft.

5. A portable bending machine as defined in claim 4 wherein said motor is carried by said upper sweep arm member.

6. A portable stock bending machine comprising, a stationary block adapted to rest in a horizontal position adjacent the floor, said block having an external arcuate grooved periphery, upper and lower sweep arms disposed adjacent the upper and lower faces respectively of said block and extending beyond the periphery thereof, means pivotally mounting said arms on said block for rotation on a common vertical axis coincident with the center of radius of said periphery, a dog disposed between and secured to both of said sweep arms beyond the periphery of said block, said block also being provided with an arcuate toothed slot constituting a rack gear arranged concentrically with the periphery thereof and disposed between said periphery and the axis of rotation of said sweep arms, an output shaft including a pinion located between said sweep arms and meshed with said rack gear, vertically aligned bearing means in said upper and lower sweep arms journaling said output shaft, an input shaft, and reduction gearing extending between said input and output shafts, said input shaft and reduction gearing being carried by said upper sweep arm.
